UNITED STATES PATENT OFFICE.

LELAND S. MAEDE, OF SAN FRANCISCO, CALIFORNIA.

CAN-FEEDING DEVICE.

1,426,659.

Specification of Letters Patent. Patented Aug. 22, 1922.

Application filed April 13, 1921. Serial No. 461,070.

To all whom it may concern:

Be it known that I, LELAND S. MAEDE, a citizen of the United States, residing at San Francisco, in the county of San Francisco and State of California, have invented new and useful Improvements in Can-Feeding Devices, of which the following is a specification.

This invention relates to a can feeding device, and especially to means for delivering and removing the cans from the vacuum chamber in which they are exhausted and sealed.

Many foods and other products are packed by the so-called vacuum process; the products being generally packed in tin cans which are delivered to a vacuum chamber wherein they are thoroughly exhausted and sealed. When sealing cans in this manner it is generally required that a vacuum of at least 28 inches be maintained. A considerably higher vacuum would, however, be preferred, for instance 29 inches or more, but present practice shows that the mechanical problems and structures involved render such high vacuums almost impossible to maintain.

It should be realized that the general type of machine employed for this purpose embodies a housing in which is formed an evacuating chamber sufficiently large to enclose a double seaming machine which is driven from an exterior source. Means are provided for delivering and discharging cans with relation to the evacuating chamber and the double seaming machine, and a driving connection is made with each of said means to permit synchronous cooperation with the double seamer. The several driving connections required are the cause of considerable leakage but the can delivering and discharging mechanism is the source of the greatest leakage.

The present invention relates to the can delivering and discharging mechanism. One of the objects of the present invention is generally to improve and simplify such mechanism, and particularly to provide a mechanism by which leakage may be reduced to a minimum.

Another object of the invention is to provide a plunger feeding and discharging mechanism; the plungers being employed for receiving the cans and alternately delivering and discharging the same with relation to the evacuating chamber. Further objects will hereinafter appear.

The invention is illustrated by way of example in the accompanying drawings, in which—

Fig. 1 is a side elevation of the can filling, topping, evacuating and sealing machine,

Fig. 2 is an enlarged cross section of the can receiving plunger and the housing in which it is reciprocally mounted,

Fig. 3 is a plan view of Fig. 1,

Fig. 4 is an enlarged detailed view of the can delivering chute,

Fig. 5 is a perspective view of one unit of the can feeding mechanism,

Fig. 6 is an end view of the can evacuating and sealing mechanism showing the position of the feeding mechanism whereby the cans are delivered thereto.

Referring to the drawings in detail, and particularly to Fig. 1, A indicates in general the can filling machine, B the can topping machine and C the can sealing machine. The several machines are independent units and are here shown as arranged in line formation, which is the usual practice in most packing plants. The present invention relates particularly to a mechanism whereby the cans are transferred from the capping unit B to the evacuating and sealing unit C, and also to the mechanism employed for discharging the cans with relation thereto when evacuated and sealed. The can delivering mechanism is generally indicated at D and the can discharging mechanism at E. The units D and E are, practically speaking, identical in construction, and both are driven in unison so as to synchronize and cooperate with the double seaming machine disposed within the evacuating unit C. The detailed construction of the can delivering and discharging mechanism is perhaps most clearly illustrated in Figs. 2 and 5, and their position with relation to the evacuating and sealing unit is most clearly illustrated in Figs. 1 and 3.

The mechanism consists of a housing, see Figs. 2 and 5, which is rectangular in cross section and composed of two sections 2 and 3, which are secured together by bolts or other suitable means. The housing sections 2 and 3 are disposed on an angle, as shown in Figs. 1 and 2, and they enclose a plunger 4 in which is formed a pocket 5. The pocket is disposed transversely of the plunger and forms an opening extending entirely through the same. The housing section 3 is provided with two entry openings 7 and 8, while the housing section 2 is provided with

a single discharge opening 9. Disposed adjacent each of the openings, and preferably formed integral with the respective housing sections 2 and 3 are shelf-like projections 10 by which the cans are delivered and discharged, said shelf-like projections assuming the same incline as the plunger and the pocket formed therein, and in fact forming a continuous surface with relation to the 10 pocket so that the cans may be delivered thereto and discharged therefrom by gravity. The can discharging unit E is identical in construction to that shown at D, as the housing encloses a plunger in which is 15 formed a pocket. One side of the housing is provided with an inlet opening and the opposite side of the housing is provided with two discharge openings, the discharge opening of the unit E communicating with the 20 evacuating chamber formed in the unit C and the inlet opening of the unit D communicating with the same chamber. As the units D and E operate in unison with each other and the seaming machine generally indicated at 12 it is obvious that a common 25 drive should preferably be provided. The drive employed in this instance consists of a shaft 13 suitably journaled on one side of the unit C. Power is transmitted to the 30 shaft in any suitable manner, or as here shown by a pulley 14. Suitably secured on each end of the unit or the housing C is a bearing bracket 15, and journaled in each bracket is a crank shaft 16 on one end of 35 which is secured a sprocket gear 17. Secured on each end of the shaft 13 are sprocket wheels 18, and forming a driving connection between the respective pairs of sprockets 17 and 18 are endless driving 40 chains 19 and 20. Secured on one side of the housing or unit C, as at 21, is a pair of bearing members 22. These are disposed one at each end of the housing, and each supports a rocker arm 23 to which an oscillating 45 movement is transmitted by connecting rods 24. One end of each connecting rod is attached to the respective crank shafts 16, while the opposite ends are resiliently attached to the rocker arms 23, as at 25, the 50 upper ends of the respective rocker arms being connected with the plungers 4 by their connecting rods 26, see Figs. 3, 5 and 6. From the foregoing it will be seen that the plungers enclosed by the respective housings 55 disposed one at each end of the evacuating and sealing unit are reciprocated in unison, said reciprocal movement being transmitted from the shafts 13 through the chain drive 20, the crank shafts 16, connecting rods 24 and rocker arms 23. The pocket 5 formed 60 in the can delivering plunger will therefore alternately register with the inlet openings 7 and 8 and with the discharge opening 9 in the unit D, and conversely the pocket formed 65 in the plunger disposed in the can discharg-

ing unit E will alternately register with the single centrally disposed inlet opening which communicates with the evacuating chamber and the respective discharge openings. The particular form of mechanism employed for transferring the cans from the unit D when admitted to the double seaming machine is only generally illustrated and may, of course, be arranged as desired; similarly the mechanism by which the cans are discharged from the double seamer and delivered to the discharging unit E. This mechanism does not form any particular part of this invention and is therefore only briefly illustrated. The packing unit A and the topping unit B are neither involved in the present invention, but merely show the general line arrangement employed in the packing plants. 70

In actual operation the cans are first delivered by a conveyor 30 into the packing unit A where the cans are filled. They are then conveyed to the topping unit B where the caps are applied and partially secured, no seal being, however, formed in this machine. The cans are then delivered one by one to the feeding unit D by a forked or Y-shaped chute, generally indicated at 31. This chute alternately delivers the cans to the respective inlet openings 7 and 8, being 80 deflected from one chute to the other by a gate or guide member 32. This guide is pivotally supported at the apex of the Y-shaped chute, as shown at 33. It is supported on a shaft, on the lower end of which is mounted a crank arm 34, see Fig. 4. A second shaft is suitably journaled at the upper end of the chute, as at 35, and this supports a bell crank 36 from which movement is transmitted to the crank 34, shaft 90 33 and guide member 32 by means of a link 37. The bell crank is in turn actuated by a pair of cam members 38 formed on the table 39 of the capping unit B. There are two of these cams disposed on opposite sides of the 100 table. When one of the cams 38 strikes the free end of the bell crank 36 movement is transmitted so that the guide member 32 assumes the position shown in Fig. 4. A can delivered to the upper end of the chute is 110 thus deflected to the opening 7. The next can delivered to the chute passes down through the other branch of the Y-shaped chute as the guide member 32 assumes the dotted line position 32^a when not actuated by one of the cams 38, the dotted line position 32^a being assumed as the shaft 32 is normally turned or held in a predetermined 120 position by the tension of the spring 40. In other words, alternate positioning of the guide member 32 is obtained by cam and spring action, but may, of course, be otherwise actuated, as any suitable means may be provided for delivering the cans 125 alternately to the openings 7 and 8. The 130

- 5 pocket of the plunger in the first unit D alternately registers with the pockets 7 and 8, and as these are disposed in an inclined position and also the pocket of the plunger 65 it is obvious that the cans will enter by gravity and similarly discharge by gravity when register is made with the discharge opening 9. Admission of air during this movement is reduced to a minimum; as it is 10 a comparatively easy matter to tightly pack the plunger such as shown at 4, the only air entering the evacuating chamber will be that admitted whenever the plunger pocket registers with the opening 9. If the cubic 15 contents of the pocket are 30 cubic inches then it is obvious that 30 cubic inches will be admitted once during each movement of the plunger. This is, however, practically speaking, all the air admitted, as leakage 20 need hardly be considered. The chamber formed within the unit C is at all times connected with a vacuum pump not here shown, through means of a pipe 50, and the vacuum maintained will therefore be comparatively 25 high as the amount of air admitted is exceedingly small. A similar volume of air is admitted during each movement of the plunger in the unit E, but the combined volume of air admitted by the two plungers will 30 in practice present the entire load imposed upon the vacuum pump. The unit E is also disposed on an incline, as shown in Fig. 1, and as such will permit the cans to enter and discharge by gravity, thus materially 35 eliminating complicated feeds and other forms of mechanism generally required. In fact, one of the most important features of the present invention is the provision of a can admitting and discharging member 40 which is so constructed that it may be readily packed against leakage. Such a feeding mechanism is without a doubt provided in this instance, as the plunger may be constructed as long as desired, thereby 45 providing large packing and wearing surfaces which can easily be taken care of.
- Having thus described my invention, what I claim and desire to secure by Letters Patent is:—
- 50 1. A can feeding device comprising a casing having a pair of inlet openings and a discharge opening formed therein, said discharge opening being located intermediate the inlet openings, and a plunger having a 55 transverse pocket reciprocally mounted in said casing, said pocket during the reciprocal movement of the plunger alternately registering with the inlet openings and the discharge opening.
- 60 2. A can feeding device comprising a casing having a pair of openings formed in one side thereof and a single opening formed in the opposite side, intermediate the first named openings, and a plunger having a 65 transverse pocket formed therein reciprocally mounted in said casing, said pocket during the reciprocal movement of the plunger alternately registering with the respective openings.
3. A can feeding device comprising a rectangular casing having a pair of inlet openings formed in one side thereof, and a discharge opening formed in the opposite side intermediate the inlet openings, a rectangular plunger mounted in said casing, said 70 plunger having a transverse pocket formed therein, and means for reciprocating said plunger whereby said pocket will alternately register with the discharge and inlet openings.
4. In a device of the character described a feeding mechanism comprising a rectangular shaped housing having a pair of inlet openings formed in one side and a discharge opening formed in the opposite side, a rectangular shaped plunger reciprocally mounted in the housing, said plunger having a transverse passage formed therein, and means for imparting a reciprocal movement to the plunger to cause alternate register of the 75 passage formed therein with the respective inlet openings and the discharge opening.
5. In a device of the character described a feeding mechanism comprising a rectangular shaped housing having a pair of inlet 80 openings formed in one side and a discharge opening formed in the opposite side, a rectangular shaped plunger reciprocally mounted in the housing, said plunger having a transverse passage formed therein, and means for imparting a reciprocal movement to the plunger to cause alternate register of the 85 passage formed therein with the respective inlet openings and the discharge opening.
6. In a device of the character described a feeding mechanism comprising a rectangular shaped housing having a pair of inlet 90 openings formed in one side and a discharge opening formed in the opposite side, a rectangular shaped plunger reciprocally mounted in the housing, said plunger having a transverse passage formed therein, and means for imparting a reciprocal movement to the plunger to cause alternate register of the 95 passage formed therein with the respective inlet openings and the discharge opening.
7. In a device of the character described a feeding mechanism comprising a rectangular shaped housing having a pair of inlet 100 openings formed in one side and a discharge opening formed in the opposite side, a rectangular shaped plunger reciprocally mounted in the housing, said plunger having a transverse passage in the plunger 105 assuming an inclined position and inclined chutes communicating with the respective inlet and discharge openings.
8. In a device of the character described a feeding mechanism comprising a rectangular shaped housing having a pair of inlet 110 openings formed in one side and a discharge opening formed in the opposite side, a rectangular shaped plunger reciprocally mounted in the housing, said plunger having a transverse passage formed therein, means for imparting a reciprocal movement to the plunger to cause alternate register of the 115 passage formed therein with the respective inlet openings and the discharge opening,
9. In a device of the character described a feeding mechanism comprising a rectangular shaped housing having a pair of inlet openings formed in one side and a discharge opening formed in the opposite side, a rectangular shaped plunger reciprocally mounted in the housing, said plunger having a transverse passage in the plunger 120 assuming an inclined position and inclined chutes communicating with the respective inlet and discharge openings and means for alternately delivering cans first to one and then the other of the chutes which communicate with the inlet openings.

LELAND S. MAEDE.
